(57) **CLAIM**

The ornamental design for a medical suction/lavage handpiece, as shown and described.

DESCRIPTION

FIG. 1 is a perspective view of a medical suction/lavage handpiece showing my new design;

FIG. 2 is a side elevational view thereof, the opposite side being identical;

FIG. 3 is a top elevational view thereof;

FIG. 4 is a bottom elevational view thereof;

FIG. 5 is a rear elevational view thereof; and,

FIG. 6 is a front elevational view thereof.

The broken line showing of the cables and tube exiting the medical suction/lavage handpiece is for illustrative purposes only and forms no part of the claimed design.
